ALBERT H. TATUM, OF NEW YORK, N. Y., ASSIGNOR TO WHITALL TATUM COMPANY, OF NEW YORK, N. Y., A CORPORATION OF NEW JERSEY.

NURSING-NIPPLE.

1,045,456.

Specification of Letters Patent. Patented Nov. 26, 1912.

Application filed March 4, 1911. Serial No. 612,262.

To all whom it may concern:

Be it known that I, ALBERT H. TATUM, a citizen of the United States, residing at New York, in the county of New York and State 5 of New York, have invented new and useful Improvements in Nursing-Nipples, of which the following is a specification.

My invention relates to a new and improved form of nipple to be used on a nursing 10 bottle for infants.

Among the many advantages of my improvement are the following: The nipple more nearly resembles the human breast than any other nipple which has been here- 15 tofore made. My nipple is so formed that the ball and elongated or teat shaped protuberance conform almost exactly to the anatomical formation of the hard and soft palate of the infant. When using a nipple 20 constructed in accordance with my invention, the infant when first taking the nipple into its mouth does not bite on the bulb itself and thus shut off the flow of milk from the bottle causing the nipple to collapse, 25 which is the great difficulty experienced in using the nipples which have been heretofore made, but the infant bites the teat shaped protuberance first and thus does not shut off the flow of liquid but allows a more 30 even flow of liquid than can be attained by using any of the shapes which are now made. I also provide against the collapsing of the bulb by reinforcing the lower half of the bulb making it of heavier rubber than the 35 front part of the bulb is made of.

In the accompanying drawing, Figure 1 represents a front elevation of my device. Fig. 2 represents a sectional view of the same. Fig. 3 is a modification showing the 40 lower part reinforced.

The device consists of a rubber nipple having a base *a* adapted to fit over the sides of the neck of a bottle not shown. The neck *c* is tapering in form being less in diameter 45 at the point *d* than it is at the mouth of the nipple. The nipple is then enlarged being spherical in form and having a bulb *e*, the diameter of which is greater than the neck *d* and nearly of the same diameter as the base 50 of the nipple. The bulb *e* gradually tapers and merges into a distinct tip *f*, the chamber inclosed by the bulb and tip having a

throat which gradually narrows as the bulb merges into the tip, there being no constriction of the throat between the bulb and tip 55 such as would make the tip itself a distinct bulb as is clearly shown in the drawing where the tip is shown as of much less diameter than the neck *d* and about the size of the nipple of the human breast. At or 60 near the end of the tip or protuberance *f* is one or more openings *g* for the milk to pass through. When the nipple is inserted in the mouth of an infant the infant's mouth closes on the protuberance *f* and does not press 65 the bulb *e* to any extent and the neck *c* of the nipple always remains open and a continual flow of milk is assured.

In the modification shown in Fig. 3, the lower part of the bulb *e* is reinforced as 70 shown at *h*. The reinforcement at this portion of the bulb minimizes the danger of the bulb collapsing and shutting off the flow of milk.

Having described my invention I claim: 75

1. A nipple comprising a base adapted to fit over the neck of a bottle, a bulb, a neck connecting the base with the bulb, the bulb gradually tapering into a tip formation, said tip gradually tapering from the line of 80 its juncture with the bulb to its end the free and unobstructed chamber inclosed by said bulb and tip having a throat which gradually narrows as the bulb merges into the tip, substantially as described. 85

2. A nipple comprising a base adapted to fit over the neck of a bottle, a bulb, a neck connecting the base with the bulb, the bulb gradually tapering into a tip formation, said tip gradually tapering from the line 90 of its juncture with the bulb to its end, the free and unobstructed chamber inclosed by said bulb and tip having a throat which gradually narrows as the bulb merges into the tip, the lower part of the bulb being 95 thickened, substantially as described.

In testimony whereof I have hereunto set my hand in the presence of two subscribing witnesses.

ALBERT H. TATUM.
